SYSTEM FOR OPERATING TRAINS

Archibald G. Shaver, Chicago, Ill.

Application October 22, 1927, Serial No. 227,932

60 Claims.

(Cl. 246—8)

This invention relates to an improved system for operating trains on a railroad, combining safety and economy through the provision of means to save time in operation and to keep trains moving.

The prevailing practice in railway train operation has been to provide a time card scheduling the rate of movement for all regular trains and the rules governing the procedure in the operation of trains. In the cases of special instructions for trains these are usually in the form of written orders transmitted to the trains enroute through local telegraph and train order stations from the dispatcher in charge of the division or district. These written orders are of two kinds, the "31 order" which the train must stop to receive; and the "19 order" which is passed up to the train as it moves by the local station, the train only slowing down for the purpose. The safety of trains is provided for by a block signal system so that a signal will indicate to an approaching train whether the block ahead is occupied. The location of trains is recorded with the assistance of the operators at local stations who report passing trains to the dispatcher. Trains about to take or leave a siding must stop, a member of the crew walks ahead and opens the siding switch, the train pulls in or out of the siding, as the case may be, and again must stop for a member of the crew to close the switch.

In the performance of these various functions in operating trains as above outlined, considerable time is lost and considerable expense is involved which it is proposed to save in the present invention, and the accomplishment of these results is the general object of the invention.

Another object of the invention is the provision of means whereby a member of the crew on the rear of a train may get into communication with a member of the crew at the head end of the train and vice versa, and whereby the dispatcher may communicate with the train at will, by telephone or otherwise, while the train is standing or in motion, thus making local operators unnecessary for the transmitting of orders, and may be telephoned to by one of the crew, at will.

Another object of the invention is the provision of means in a system such as described, whereby the dispatcher may inform himself as to the location, direction of movement and approximate rate of travel of any train in the district, thus making operators at local stations unnecessary for transmitting such information.

55 A further object is the providing of means in

a system embodying the other features enumerated, by which the dispatcher can give notice to a train to take siding and be advised that such means has operated.

A further object is the providing of signal protection, under the control of the dispatcher, at a track switch, to not only stop the train from further main line movement but to protect it against any opposing oncoming train. In such display of the signals by the dispatcher he is advised by appropriate means that the signals have operated.

Another object is to provide means whereby when the take siding signal is displayed the train, without coming to a stop, may operate the switch to divert itself, from the main line into the siding and failure to operate the switch properly will result in the train being automatically stopped.

Another object is the provision of a system such that the siding switch may be operated by either the dispatcher or by approaching trains and the dispatcher advised in either case when the switch operates.

A further object is to provide means whereby the dispatcher may, at his option, control trains in leaving a siding.

Another object is the provision of means giving audible information to the dispatcher on the operation of the controlling instrument governing the signals or switches, or both.

Another object is to provide an arrangement of apparatus such that when the signals have cleared, the siding switch must be in a certain position agreeing with the cleared signal.

Another object is to provide an arrangement whereby the dispatcher may operate certain signals at the switch, after which he may then restore the arrangement to its normal condition, without the necessity of operating the switch.

An additional object relates to the arrangement of means whereby, when the route is set for the trains to proceed into the siding, any train control restriction existing is cancelled.

Other objects of the invention will appear in the description of the preferred embodiment of the invention which follows:

Figs. 1 and 5 are diagrammatic illustrations of the system, the latter figure being a continuation of the former.

Fig. 2 is a detail of the arrangement of the inductors and connected telephone apparatus on the trains, for the communicating system.

respects from that shown in Fig. 1 in that resistances are shown around the insulated track joints instead of condensers.

Fig. 4 is an illustration of an apparatus for opening and closing certain circuits in a selector system, and

Fig. 6 is a modification of the main telephone circuit or a part thereof.

The system consists generally of a complete train protecting and operating system, so constituted that the dispatcher may determine the location and direction of travel of the trains, and may talk by telephone directly with the attendants on the train, without the necessity for intermediaries or station operators, in issuing orders and instructions; the attendants on the front and rear of a train may communicate with each other and with the dispatcher at will.

The dispatcher may give verbal instructions to the train attendants to take the train in on a certain passing siding to allow another train to pass. Having done so, he may provide a check on these instructions in the way of the display of a take siding signal. Additionally, he may set the signals for each direction at the track siding switch so that the two trains will be protected, each against the other. A train receiving instructions to take the siding, may operate the siding switch from the train as it moves along. Failure to operate the siding switch will result in an automatic application of the brakes to stop the train, through the operation of train control means as will be hereafter explained. Should the dispatcher deem it advisable to operate the siding switch himself he may do so.

In Figs. 1 and 5 the signal system indicated is that in general use on the railroads, preferably of the type of automatic block signals. For convenience and flexibility in operation, the annunciator or novel train indicator system is divided into two parts—one (the station group) embracing the tracks included within the limits of the passing track, and the other (the road group) comprising the stretch of track between two adjacent stations as X and Y.

The station group includes the track circuits S1 to S6 inclusive (Fig. 1) with corresponding relays P1 to P6 inclusive. The road group includes the track circuits C1 to C7 inclusive (Figs. 1 and 5). The principle of operation of this train indicator system is that of inserting or eliminating resistances, preferably of the adjustable type, in a circuit containing a source of energy and an indicating instrument on the order of an ammeter, as claimed in the application of Allen B. Kendall, Serial No. 223,663, filed October 3, 1927, now Patent No. 1,827,020, granted October 13, 1931, whereby the dispatcher may readily locate a train and note its direction of travel and approximate average speed.

Considering the station group, as at X, the train position indicating circuit normally comprises battery B1, resistance R1, conductor 12, resistance R6, conductor 11, resistance R5, conductor 10, resistance R4, conductor L4, resistance R3, conductor 9, resistance R2, conductor 8, resistance R1, conductors 7, D1 and 130 (Fig. 5), contact 131 normally open, conductor 132, indicating instrument SQ, conductor 133, contact 134 normally open, conductors D3 and 14, and contact 13 normally open to battery B1. In parallel with resistance R1 is back contact 1 of track relay P1. With contacts 13, 131 and 134 closed and a train in track circuit S1, resistance R1 is shunted from the circuit by contact 1 closed and conductors 16

and 19, so that the dispatcher's instrument SQ will register, for example "1", all the other resistances R2 and R7 being in circuit. With a train in track circuit S2, resistances R1 and R2 are shunted from the circuit by contact 2 closed and conductor 17 and instrument SQ will read "2"; with a train in track circuit S3, resistances R1, R2 and R3 are shunted from the circuit by contact 3 and instrument SQ reads "3", etc. With a train in track circuit S6 all the resistances 10 are shunted from the circuit by contact 6 but R7 and instrument SQ will read "6".

Instrument SL1 (Fig. 1) is represented as a relay controlled by the dispatcher's selector system. CB (Fig. 5) represents a selector key mechanism in the dispatcher's office for controlling a selector along the railroad. Each key controls the sequence of impulses required in the code for operating the selector with which it is aligned. B3 is the source of energy for the impulses which are sent out in the operation of the selector keys to control the various selectors. The station group instrument SQ and the road group instrument RQ are located in the dispatcher's office. Normally they are out of circuit, but either can be inserted in the circuit by operation of its respective button 135 or 136.

If the dispatcher desires to know if there is a train at station X, he operates the appropriate selector code to energize SL1 to close contact 13. He then pushes button 135 which connects instrument SQ in the circuit. By the indication of the pointer SQ he can tell if there is a train at station X and the track circuit in which it is located. If the indication of SQ changes from 2 to 3 to 4, etc., the dispatcher knows the train is travelling toward Y. If the indication of SQ changes decreasingly from 5 to 4 to 3, etc., the dispatcher knows the train is traveling from Y towards X. If the indication of SQ changes from 5 to 6 to 1, the dispatcher knows the train is entering the siding passing over sections S5, S6 and S1 and moving away from Y. By noting the rate of change of indication of SQ and knowing the length of the track circuits, the dispatcher can determine the average rate of speed at which the train is traveling.

Considering the road group, the arrangement of the circuits and the operation are similar to those explained for the station group at X. For example the track circuit sections C1, C2, . . . C7 are each provided with correspondingly numbered relays T1, T2, . . . T7, controlling resistances Q1, Q2, . . . Q7, said resistances being normally in series with instrument RQ, when contact 28 and the switch 136 are closed, and with battery B2. If the dispatcher desires to know if there is a train in any of these sections he operates the selector key mechanism to energize SL2 (Fig. 5) and closes contact 28 and observes the pointer of the instrument RQ which indicates the location and direction of travel of the train.

As shown there is a battery as B1, B2 etc., for each group. If so desired, the source of energy may be located in the dispatcher's office and only one will then be required, and not one for each group.

Having located the train, which may be moving or standing still, the dispatcher is able to get directly in communication with the crew to communicate orders and information.

Figure 2 represents the train telephone system provided to permit communication between the front (locomotive end) and rear (caboose end)

of the train. A and B may each be considered as combined telephone transmitting and receiving sets on the locomotive and caboose respectively. 250—251 and 252—253 represent inductors connected with the telephone sets A and B respectively and so located on the train as to ride close to the track rails. In the case of attendant at A talking to attendant at B, the voice currents set up in the inductors 250 and 251 are in the same directions and are induced into the track rails in the same direction. The currents set up in the track rails affect the inductors 252 and 253 and are transmitted to the receiver of B. The operation is reversed in the case of B talking to A.

In Fig. 2 the pairs of inductors at the front and rear ends of the train are shown connected in parallel. It should be understood they may also be connected in series. While I have designated this system specifically as a telephone system, it should be understood that the same general method may be used for other forms of communication and transmission of impulses for both audible and visual indications.

I shall now describe the roadside features of the system and how the roadside and train features co-operate. There are a series of local intermediate circuits along the railroad, forming what may be termed a travelling circuit or zone for each train. They comprise the track rails and a line conductor, the two being suitably connected together at intervals; and a transformer is included that the dispatcher may connect his telephone system in circuit as he desires. As the track rails are divided into sections for track circuit purposes, the sections being separated by insulated joints, it is considered desirable that means be provided for conducting the communicating current around the insulated joints, hence the condensers C are used at all the insulated joints, or the resistances r may be used, as shown in Fig. 3. Insulated track joints, under usual service conditions, are of low impedance for telephone currents. The few usually occurring in intermediate circuits of moderate length are not an appreciable obstacle to the flow of voice currents. However, under certain track conditions, and with intermediate circuits containing a considerable number of insulated joints, or for types of communication requiring more current than telephony, current flow to the receiver is improved by providing means to conduct or bypass the communicating current around the insulated joints. Condensers, where used, pass the communicating current, which is intermittent in character, but provide a barrier for the current which is used for track circuit purposes. Instances used around insulated joints are of a character to offer small impedance to the communicating currents, but obstruct the flow of the track circuit current.

One typical district of this intermediate circuit comprises track rails at circuit C1, conductors 64 and 65 connecting through condensers K to conductor 66, contact 67 normally closed, conductor 68, transformer primary p of TF2, conductors 69, D3 and 81, primary P of transformer TF3, conductor 80, contact 78 normally closed, conductor 78, condensers K and conductors 16 and 11 connecting to track rails in section C4 and then via the track rails and conducting medium around insulated joints of sections C3 and C2 to section C1. In communicating, the transmitting inductor on the train induces intermittent current into this intermediate circuit, which is complete

in itself, and the receiving inductor on the train receives the intermittent current carrying it to the receiver. The communicating current is received into and transmitted from the track rails, and the circuit just described is in reality an intermediate or carrier circuit for the territory including sections C2 and C3. Assume the train is moving in the direction from X toward Y; when in section C4 relay T4 is de-energized opening contact 79. The intermediate circuit is therefore extended ahead of the train and is the same as above described, except the circuit is no longer complete through contact 79, but is complete through conductor 93, primary P of transformer TF4, conductor 92, contact 91, conductor 90, condensers K, conductors 88—89 and track rails back to the conductor connections 64—65. After the train clears the track section C4, it is then in the intermediate circuit for district C5 and C6, comprising, track rails including condensers C around insulated joints, conductors 16 and 11 connecting through condensers K to conductor 78; contact 78 again closed, conductor 80, primary P of transformer TF3, conductors 81, D3 and 93, primary P of transformer TF4, conductor 92, contact 91 normally closed, conductor 90, and conductors 88 and 89 connecting through condensers K to track rails. Communicating impulses from and to the inductors on the train are now carried in this circuit instead of in the enlarged circuit for the two districts C2—C3 and C5—C6 as heretofore explained. It will be observed, therefore, that the train carried inductors are always within, and in inductive relation with, an intermediate circuit which is, in effect, a circuit or zone traveling with the train, and which, for convenience, I have designated a travelling intermediate circuit or zone. This arrangement is especially advantageous for rear end communication in that communication between the two stations on the different parts of the train may be maintained continuously, as the train operates through the equipped territory, and yet confined to the zone in which the train operates. It is obvious that for a plurality of trains operating within the equipped territory, or a stretch of railway, each may be maintained in a communicating zone of its own that communication may be carried on between stations on different parts of said train or between said train and a wayside station, without interfering with the communication of other trains in the same territory. It may be further noted that where trains operate within the same communicating zone, for example, when passing at siding locations, they may communicate with each other in the same manner as where communication is carried on between the rear end and head end of a train. This is of advantage from the standpoint of safety and efficient train operation.

When the dispatcher desires to communicate with a train, he operates the appropriate selector in his telephone system to cut himself in on the intermediate circuit. For example, with a train in the intermediate circuit described, he may operate selector SL4 to close contacts 72 and 73 which connect the leads 70 and 71 of the secondary s of transformer TF2 directly on to dispatcher's telephone line, conductors D1 and D2. He is then in position to talk to the crew in both the front end and rear end of the train, and they can talk to him. When through communicating with the train he again operates his selective apparatus and disconnects the intermediate circuit from his telephone line.

It is desirable that the communicating currents have the same characteristics in both track rails. The connection of the line part of the intermediate circuit is made to the track rails through condensers K in order to make both track rails as nearly like one conductor as possible for communicating purposes, yet to cause no interference with the proper operation of the track circuits. The communicating current is intermittent or alternating in character. Its direction at any instant in the two track rails, when induced therein, is the same. From the track rails the communicating current passes through the condensers K and the cross conductor and transformer at one end of the intermediate circuit to the conductor D3 and thence back through the cross conductor, transformer and the condensers K at the other end of the circuit to the track rails, thence through the track rails and the bypasses thereon at the insulated joints. When the dispatcher talks to the train, communication current from his circuit, conductors D1 and D2, is induced into the intermediate circuit at the transformers, as TF2, and passes through the intermediate circuit as above described. This communication current in the track rails is reintroduced into the train carried inductors and carried to the train communication receivers. Communication current originating on the train is induced from the inductors into the track rails of the intermediate circuit and thence through the transformers, as TF2, into the dispatcher's communicating circuit, conductors D1 and D2, and receiver.

A chief value of this communicating system lies in the ability of the conductor in the caboose at the rear end of a long train to communicate with the engineman in the locomotive at the front of the train, thus having an understanding at all times as to the conduct of the train, such as making meeting points, setting out and picking up cars, taking water and coal, etc. The usual method of communication between caboose and locomotive practiced at the present time is that of hand and whistle signaling. With this improved communicating means, the train is operated more efficiently and much time is saved in getting it over the railroad.

Another chief advantage of this communicating system lies in the facility with which the dispatcher may communicate with a train to change its instructions, warn of dangers, and the like; all tending to facilitate the movement of the train and increase its safety.

If it is desired to have the train automatically connected to the dispatcher's communicating system for some locations or at all times so that those on the train may freely communicate with the dispatcher without waiting for the dispatcher to cut in his own circuit first, the arrangement shown in Fig. 6 is provided. This diagram is only fragmentary being in practice a part of the circuit shown in Figs. 1 and 5. The transformer TF may be any one of the transformers TF1, TF2 etc., shown in said figures and in each case the secondary is connected through leads 201 and 206 through the back contacts 202 and 205 of a relay RC, direct to the dispatcher's circuit D1, D2 through conductors 203 and 204. The relay RC may be either a track relay, such as T1 and T2 etc., or a relay such as the control relay of the signal system which is itself controlled by the track relay or a plurality of track relays. As the train progresses from one section to another, it is always connected to the lines D1, D2 through the de-energization of the corresponding relay.

This dispatcher circuit D1, D2 may be a commercial telephone circuit whereby passengers on a passenger train for example, may carry on conversation with parties in distant cities and vice versa.

In the case of a train taking a passing siding, the dispatcher may give such instructions through the display of a "take siding" signal 115; or he may display this signal in addition to having given the train crew written or verbal instruction. He may also set the signals at the switch as H9 and H10, in the stop condition to close the main line to the train required to take the siding and to stop any opposing train from proceeding by the fouling point of the main line and the siding. He may also open the circuit for signal H12 to hold that signal at stop so that a train standing on the siding will be held there until permitted to move out on the main line.

The "take siding" signal and the signals H9 and H10 may be either the light or semaphore type and the circuits include the usual features as described below. Both signals H9 and H10 govern along the main line and both are in the stop position with switch SW open. The control for light type and semaphore signals is much the same in either case. For convenience semaphore signals are shown at the switch and the "take siding" signal is a sign operated by the same sort of mechanism as the semaphore signals. Normally, the "take siding" signal is withdrawn from display, and the signals H9, H10, H11 and H12 are in a condition to operate the same as in any automatic signal system.

By operating the controlling instrument SD, shown in Figs. 4 and 5, the control energy is cut off for the display of the "take siding" signal and the placing of signals H9 and H10 at stop. Relays N9, N10, N11 and N12 are the control relays for the signals H9, H10, H11 and H12 respectively. Control relay N9 is controlled by track circuits C8, C9, etc. through the block as indicated by the broken line 208. Control relay N10 is controlled by the track circuit C8, C7, C6 and C5 as indicated by the broken line 207. In the case that the signal system is an automatic permissive system (APB) relay N10 would be controlled by track circuits C8, C7 and C6 for following train moves but for opposing or head on train moves, it would also be controlled by the additional track circuits C5, C4, C3, C2, C1 and S5. Control relay N11, as indicated by the broken line 210, is controlled by the track circuit C8. Control relay N12, as indicated by the broken line 207, is controlled by the same track circuits as control relay N10. The blocks for the signals H9, H10, H11 and H12 correspond to the territory covered by the track circuits controlling the respective control relays for these signals. With the controlling instrument SD (Figs. 4 and 5) in its normal position and the blocks of signals H9 and H10 occupied, relays N9 and N10 are de-energized.

The controlling instrument SD, comprising a series of commutator segments or contacts, controls electric circuits through electromagnets operated by selectors SL1 and SL2. This is shown in detail in Fig. 4, where 155 and 169 are electromagnets which are in local circuits controlled by selectors 161 (SL1) and 176 (SL2) respectively.

Commutator segments 100, 101, etc., are located on the same shaft with the ratchet wheel or gear 154, and as shown have six positions; though they may have any number of positions 75

from two up as required. When magnet 155 is energized, armature 166 is raised, lifting arm 157 which impinges on the ratchet wheel 154 turning it and commutator segments 100, 101, etc., counter-clockwise to the next position, thereby retaining a circuit closed, or opening a circuit, or closing a circuit, whichever may be considered necessary. When the selector 161 is operated by the dispatcher, it closes its contact 162 for a short interval of time, energizing electromagnet 155 from battery 163 through contact 162, conductor 153, electromagnet coil 155 and conductor 165. Each time the dispatcher operates selector 161, electromagnet 155 is energized stepping commutators 100, 101, etc., around to another position, until the first or normal position is again returned to.

Electromagnet 169 with its armature 171 and arm 170 is similar to electromagnet 155 and related parts and is for the purpose of moving ratchet wheel 154 and connected commutators 100, 101, etc., clockwise. After commutators 100, 101, etc., are moved counter-clockwise to some position as 2 or 3 to accomplish a particular purpose, it may be desirable to return them to normal position by a reverse movement and not complete the cycle of movements. Where such is the case, the dispatcher will operate selector 176 energizing electromagnet 169 from battery 163 through conductor 177, contact 175, conductor 172, electromagnet coil 169 and conductor 173. The energizing of electromagnet 169 steps commutators 100, 101, etc., around clockwise, and thus they may be returned to their normal position.

In order that the proper sequence of operation of devices may be provided in the system as shown in Fig. 5, counter-clockwise movement of commutator segments 100, 101, etc., is provided without restriction, but a stop (not shown) is provided for clockwise movement such that commutator segments may be returned to normal position but clockwise movement cannot be had beyond that point, as advancing position 6 to position 1.

Commutator segments 100 to 108 are shown in their normal position, which may be considered as position 1. The operation of these segments as shown, to accomplish the purposes desired in controlling functions is counter-clockwise and in order positions 2, 3, 4, 5 and 6 if the complete cycle is followed.

Normally the commutator segments control circuits as follows: 100 keeps circuit for control relay N12 closed in positions 1 and 5 and open in other positions; 101 keeps circuit for control relay N9 closed in positions 1 and 2 and open otherwise; 102 keeps circuit for control relay N10 closed in positions 1 and 2 and open otherwise; 103 keeps circuit for control relay 123 (take siding signal) closed in positions 1 and 2 and open otherwise; 104 closes circuit for bell 109 in position 3 but keeps it open otherwise; 105 keeps circuit for track switch controlling relay AR6 closed in all but positions 2 and 6; 106 closes circuit of controlling relay AR6, around stick contact A29, momentarily when moving between positions 3 and 4; 107 keeps circuit for bell 129 closed in positions 3, 4 and 5 but open otherwise; 108 keeps circuit for transmitter 110 open in position 1 but closed otherwise.

Signals H11 and H12 can operate to indicate clear only when switch SW is open, that is for short interval of time in the movement of segment 106 from position 3 to position 4, will energize relay AR6, since this contact 106 is also in

SW cannot be operated when track section C8 is occupied.

The switch SW is operated by the mechanism SM through control exercised from an approaching train or by the dispatcher. The arrangement of apparatus and circuits for the control of this switch from a train may be that shown in my application Serial No. 198,824 filed June 14, 1927, now Patent No. 1,913,729, granted June 13, 1933. I1 and I2 are the track inductors for the switch operation, and other similar parts here shown have the same numbers herein as in the application referred to except the prefix A is added. Relays AR4 and AR5 are normally deenergized, and in circuit connection respectively with the coils of inductors I1 and I2. The circuit connecting the inductor I1 with relay AR4 includes inductor I1, conductor A13 (indicated broken in Fig. 5), coil of relay AR4, conductor A12 (indicated broken), contact A14 normally open, and conductor A11 connecting to the other end of the coil of inductor I1. When a train enters track section C1, track relay T1 is deenergized closing contact A17. A predetermined time must elapse after the closing of contact A17 before time relay AR3, which is in a circuit energized by battery AB3 and controlled by contact A17, closes contact A14. This predetermined time is equal to the time which must be consumed by the train, after entering track section C1, before the train carried inductor comes into correspondence with the roadside inductor I1 in order to be effective in energizing the circuit of the latter including relay AR4. This time interval may be varied through adjustment of the time required for instrument AR3 to close its contact A14. Since inductor I1 is located in proximity to switch SW and the train must approach inductor I1 under restricted speed, it follows that the speed of the train cannot be excessive over the switch SW into the siding.

When a train is in the track circuit section C1 approaching the switch SW and it is desired to set the switch to divert the train into the siding, the engineman closes a circuit on the train energizing an inductor attached to the train. On correspondence of the energized train carried inductor with the inductor I1 the circuit of the latter is energized causing the relay AR4 to close the contact A25. When a train on the siding desires to come out on the main line, the energizing of the train carried inductor will, on correspondence of the train inductor with inductor I2, energize the circuit of the latter causing relay AR5 to energize closing its contact A26. The details of the operation of the switch, due to the closing of contacts A25 and A26, will hereinafter be explained.

AR6 (Fig. 5) is the control relay for operation of the switch mechanism SM. When energized it opens the switch. When de-energized it closes the switch. Normally it is de-energized. Its normal stick circuit comprises battery B4, contact A29 open, conductor A21, coil of relay AR6, conductor A22, commutator segment 105 position 1 closed, relay contact A23 closed and conductors A24 and C to battery. In this condition, the closing of either contact A25 or A26 from train carried means, which contacts are in multiple with stick contact A29, will energize relay AR6 and cause it to remain energized because of the sticking of contact A29. The operation of commutator contact 106, which is closed for a short interval of time in the movement of segment 106 from position 3 to position 4, will energize relay AR6, since this contact 106 is also in

multiple with stick contact A29. The circuit involved in the closing of contact 106 comprises battery B4, conductor A17, contact 106 closed between positions 3 and 4 of segment, conductors 5 A20 and A21, coil of relay AR6, conductor A22, contact 105 closed in position 4, contact A23, and conductors A24 and C to battery B4. When relay AR6 is energized it closes its contact A29 thus sticking itself. With contact A27 closed on 10 its front point with AR6 energized, a circuit is completed to switch mechanism SM comprising battery B4, conductors C and A24, contact A23 closed, contact 105 closed, conductor A22, contact A27 closed on its front point, conductor A31, 15 circuit contact A32 associated with stop signal H9 closed, switch mechanism SM and conductors A30 and A17. This circuit closed causes the switch SW to be opened for the siding. With relay AR6 de-energized, the circuit for mechanism SM, to close switch SW for the main line movement, comprises battery B4, conductors C and A24, contact A23 closed, contact 105 closed, conductor A22, contact A27 closed on its back point, conductor 179, switch mechanism SM and 20 conductors A30 and A17.

The switch mechanism SM may be any one of several well known types. The one referred to here comprises a mechanical system operated by an electric motor which rotates in one direction 30 to open the switch and in the opposite direction to close the switch. A pole changing circuit device is built in with the mechanical system such that it is operated by the last few rotations of the motor armature, shifting the circuit connections of the motor for operation in the opposite direction as soon as the relay AR6 is in the corresponding position.

It will be noted that the signal H9 must be in the stop condition and track section C8 uncoupled before the switch SW can be operated to the open position and that the energizing of relay AR6 places signal H9 at stop by the opening of back contact A28 de-energizing the circuit of relay N9 which controls signal H9. Also, it will 40 be noted that the sequence of operation in the device SD is such that signals at the switch SW must be at stop before AR6 can be energized by the operation of SD.

Normally relay 123, (Fig. 1) which controls 50 take siding signal 115, is energized from common conductor C, conductor 122, relay coil 123, conductors 124 and 125, commutator contact 103 closed in positions 1 and 2, conductor A30 and battery B4 to common. With commutator contact 103 being shifted to position 3, when instrument SL7 is operated, battery B4 is disconnected from relay 123, which becomes de-energized opening its contact 116 and the normally energized circuit for signal 115 of which conductors 114 and 117 are a part, causing the "take siding" signal 115 to display. Also contact 121 is closed, connecting battery 119 to conductor 125 and to relay coil 123. Battery 119 is of insufficient voltage to operate relay 123, but it is strong enough 60 to ring a bell 109, thus informing the dispatcher of the operation of the signal. With commutator contact 104 closed in the position 3, bell 109 rings through the following circuit; from common conductor C, conductor 126, bell 109, conductor 137, back contact 138 closed, conductor 142, back contact 140 closed, conductor 128, commutator contact 104 closed in position 3, conductor 125, which is normally a part of the circuit for relay 123, back contact 121 closed, contact 118 closed 70 of track relay for section C6, battery 119 to com-

mon conductor C. Under such conditions, bell 109 may continue to ring in the transmitter 110 until the approaching train gets into track section C6, when contact 118 is opened and the bell stops ringing.

To indicate to the dispatcher that signal H11 has cleared, the bell 129 rings when in the closed circuit comprising common conductor C, commutator contact 107 closed in positions 3, 4 and 5, conductor 127, bell 129, conductor 128, front 10 contact 143 (of relay N11) closed, conductors A30 and A17 and battery B4.

The transmitter equipment 110 is connected to dispatcher's telephone line conductors D1 and D2 by commutator segment 108 in all positions 15 except position 1. 149 is a switch for connecting transmitter equipment 110 to dispatcher's telephone line in case a member of a train crew or other person wants to talk to dispatcher.

Near the switch SW is a cylinder 158 in which 20 is a piston connected to said switch by rod 159. 180 is a pipe leading to whistle 150 (shown grouped with the bells and the transmitter 110). When the switch is moved, the piston moves with it, either forcing out or drawing in air through 25 whistle 150 causing same to sound in transmitter 110 every time the switch is moved and thus signal the dispatcher. This piston may be connected with the means locking the switch so as to sound 30 every time the switch is locked in position.

Gongs 167 and 168 (Fig. 4) are sounded for the operation of electromagnets 169 and 155. When armatures 171 and 166 return to their normal position, after being raised by their respective magnets to step the commutator segments 35 around, they tap the gongs 167 and 168 respectively, thus advising the dispatcher of the operation. As these gongs are of different tones, the dispatcher can tell which electromagnet is operated and in which direction the commutator is 40 rotated.

This Fig. 4 illustrates the arrangement of instruments which may be used for SL1, SL2, etc., but there need be only one selector, and rotation in stepping up would always be in the same 45 direction, as counter-clockwise. Instead of the arrangement of commutators for SD all in one shaft, with a selector for each direction of rotation, I may prefer in some cases to operate part 50 of the commutators on one shaft, as those controlling signals, by one selector, and the rest, as those controlling the switches, on another shaft controlled by another selector, the rotation being in one direction in each case.

Should the dispatcher desire information as 55 to the train, he may set the commutators of SD in position 2, when under the regular procedure of traffic he could always hear an attendant shouting the number of the train into the transmitter 110 as the train passed by. By setting the 60 commutators in the position 3, the dispatcher would be informed of the operation of the switch SW through the blowing of the whistle 150 in the transmitter 110. Thus there would be no necessity for station operators to be employed to give 65 such information.

While the commutators 100-8 are in the normal position the various signal control relay circuits are completed through them in series with the contacts (not shown) of track section circuit 70 relays, so that the signals will operate automatically unless the dispatcher intervenes. For example, the circuit for control relay N12 begins at common wire C and passes through switch circuit controller contact A47 closed only when 75

switch SW is open (set for the siding), relay coil N12, commutator contact 100, and thence through the front contacts of various track relays for the track sections constituting the block for the signal, in this case section C8 to C5 inclusive. The circuit of control relay N10 begins at common wire C and passes through relay coil N10, switch circuit controller contact 211 closed when the switch SW is closed, commutator contact 102, and thence through the contacts of various track relays the same as for N12. The circuit for control relay N9 begins at common wire C and passes through the coil N9, commutator contact 101, switch circuit controller contact A39 closed when the switch is closed, conductor A40; contact A28 closed when relay AR6 is deenergized, and thence through the front contacts (not shown) of the various track relays for the track sections of the block as C8, C9, etc. The circuit for control relay N11 begins at common wire C and passes through coil of relay N11, back contact closed when relay N9 is deenergized, switch circuit controller contact A44 closed only when switch SW is open (set for the siding) and thence through a contact (not shown) of track relay T8 to common C.

A considerable variety of train operating conditions may be taken care of with this system and some of them will now be explained together with the procedure in each case.

Assume two scheduled trains are to meet and pass at station Y and that the train coming from station X is to take the siding while the train bound toward station X keeps the main line. The latter, if it arrives first at station Y, stops on the main line before passing signal H10. The train which is to take the siding and which must be running under the prescribed speed, operates the switch in the usual way as heretofore herein explained and as also explained in my application Serial #198,824. When it has cleared the main line, including the limits of track section C8, the switch SW returns to normal position, signal H10 clears automatically and the train on the main line proceeds to X. It is noticed that each train takes care of itself in this procedure and the dispatcher is not necessarily involved. As the train bound toward X approaches station Y, it enters the block of signal H9, including track circuit sections C9 and C8, deenergizing control relay N9 which in turn sets signal H9 at stop and holds said signal in the stop condition so long as any of the track circuit sections C8, C9, etc. are occupied by the train. As the train bound toward Y passes signal H3 if the automatic block signal system is of the APB type, or as it enters track circuit section C5 in case the automatic block signal system is of the ordinary or old style, signal H10 is set at stop and remains at stop so long as any of the track circuit sections intervening between the entrance to the block and the signal H10 are occupied by the train. The setting of signal H10 at stop is accomplished through the deenergizing of relay N10 which is controlled by the track circuit sections referred to. Signal H10 being at stop, train bound toward X will not pass it. Signal H9 being at stop, train bound toward Y, which is to enter the siding, will not pass it till authorized to do so.

When the train bound toward Y is in the track circuit section C7 the engineman energizes the inductor on the train and reduces speed if necessary so that on correspondence of the train inductor with inductor II the switch is operated to the open position, signal H9 being already at

stop closing circuit controller A32, to divert the train on to the siding as heretofore explained. On the switch reaching the open or diverting position, circuit controller contacts A47 and A44, which are normally open, are closed in the circuit of relays N12 and N11 respectively; and circuit controller contacts A39 and 211, which are normally closed, are opened in the circuits of relays N9 and N10 respectively, as soon as the switch SW starts to open. As indicated by the broken line 209, these circuit controller contacts are connected to the switch and operated thereby. The closing of contact A44 permits control relay N11 to energize clearing signal H11 which is the authority for the train to proceed into the siding. As the train enters track circuit section C8, relay T8, which controls the circuits of control relay N9, N10, N11 and N12, (circuit contacts not shown in Figure 5), is deenergized, opening the circuits of these relays and consequently placing signal H11 at stop. Also, with the deenergization of relay T8, contact A23 is opened in the switch operating circuit, making it impossible for the switch SW to be operated while any part of the train is in the track section circuit C8, and relay AR6 is deenergized. After its first energization due to correspondence of train inductor with wayside inductor, relay AR6 was maintained energized through its stick contact A29. When the train clears the limits of track section circuit C8 in the siding, relay T8 is again energized closing its contact A23. Since contact A27 is now closed on its back contact, mechanism SM is operated automatically returning the switch SW to its normal or closed position, the circuit therefor being heretofore explained. With the start of the closing of switch SW, switch circuit controller contacts A47 and A44 are opened and with the completion of the closing of switch SW, contacts A39 and 211 are closed. The closing of contact 211 permits relay N10 to energize, providing the track section circuit relays in its circuit are all energized and the circuit is otherwise closed; and consequently signal H10 clears authorizing the train bound toward X to proceed on its way. In the making of this meeting point, if the train bound towards X was late so as not to have placed signal H9 at stop for train taking siding, this signal H9 would have been placed at stop nevertheless, by the energizing of relay AR6, opening back contact A28, as a consequence of the wayside inductor being energized from the train carried inductor for opening the switch. By this means contact A32 connected with the operation of signal H9 would be closed permitting the opening of the switch SW.

Assume that the train which is bound toward X takes the siding at Y at the other end (extreme right hand end, not shown). The dispatcher, as a precaution, may operate his selector SL7 (161) stepping the commutators 100-108 to position 2. This opens the circuit for signal H12 at contact 100 so it cannot clear and it also opens the circuit for relay AR6 at contact 105 so that siding switch cannot be opened by the train coming from X should the engineman, under a misapprehension, be disposed to do so. After the train from X has cleared the switch SW on the main line, the train on the siding may desire to come out on the main line to proceed to X. Two courses of procedure are now open to the dispatcher. He may step commutator segments 100-108 back to normal position by operating selector SL8 and thus let the train on the siding operate the switch SW, either by hand or from

- the train through inductor I2, after which signal H12, providing the block is clear, will clear automatically giving the train the right to proceed toward X. Or the dispatcher may decide to himself operate the switch SW for the train to come out on the main line, in which case the procedure will be:
- 1st. Operate selector SL7 to step commutator segments 100—108 to position 3, which operation sets signals H9 and H10 at stop because of the opening of contacts 101, and 102; causes bell 109 to ring, by closing contact 104 and opening contact 103, indicating that signals H9 and H10 are at stop; and closes circuit for relay AR6 at contact 105.
- 2nd. Again operate selector SL7 to step segments 100—108 to position 4, which operation energizes relay AR6 to operate mechanism SM to open switch SW by closing circuit in contact 106 momentarily as segment moves from the position 3 to 4; causes whistle 150 to sound because of movement of switch; and results in relay N11 becoming energized which, together with the closing of contact 107, causes bell 129 to ring, indicating switch is opened and locked.
- 3rd. Again operate selector SL7 to step commutators to position 5 which operation closes contact 100 clearing signal H12 and keeps bell 129 ringing by contact 107 remaining closed.
- Since signal H12 is now clear, the train proceeds out on the main line towards X. As the train enters track section C8, relay N11 is de-energized (circuit for this relay through contact of track relay T8 not being shown) and bell 129 stops ringing, signifying to the dispatcher the train is proceeding in section C8. As the train enters section C8 contact A23 is opened de-energizing relay AR6 so that switch SW automatically returns to normal or closed position as soon as train clears section C8. In this operation whistle 150 is sounded notifying dispatcher switch SW is returned to closed position.
- During this time contact 108 has been closed, except in position 1, cutting in the transmitter so that the dispatcher has heard the bells ring and whistle blow in the various positions and even could hear the train pass out. If required, a member of the crew on the rear end of the train could shout the number of the train into the transmitter, as he passes by.
- 4th. The dispatcher again operates the selector SL7 which steps the commutators 100—108 to position 6 which opens up circuit for relay AR6 at contact 105, but serves no useful purpose in this particular operation. The opening of the circuit at this point is simply to enable the dispatcher to return the switch SW to its normal condition if at any time he should open it and a train not pass through.
- 5th. Finally the dispatcher again operates selector SL7 and steps commutators 100—108 to their normal or number one position, which operation leaves all signals and apparatus in normal condition.
- It is noted that in the above case the dispatcher has control over the departure of the train from the siding and that the extent to which he takes control rests with him.
- Assume two trains on the railroad which are nearing each other and a passing siding to meet and pass. It may be further assumed that neither train knows of the other. By operating his train indicator equipment, heretofore described, the dispatcher locates each train and determines where they shall meet and pass. He then operates the appropriate selectors which will bring him into telephone communication with each train. He then instructs the trains where they shall pass and which shall take siding. He now operates selector SL7 as required to bring the commutators 100—108, at the siding where the trains are to pass, to position 3; this cuts in the transmitter 110 in the dispatcher's telephone line, places signal H12 in the stop condition, sets signals H9 and H10 at stop, displays take siding signal 115, closes contact 105 in circuit of relay AR6 so that the track switch may be operated, and results in bell 109 ringing, notifying the dispatcher that signals H9 and H10 are at stop and take siding signal 115 is displayed. One of two procedures may now be followed, the dispatcher may continue the operation of controlling instrument SD to open the switch or he may decide to let the train which is to take the siding operate the switch. The latter will be the usual course. Each method of operation has been heretofore explained. In case of the switch being operated by the train, the dispatcher knows when the switch has opened by the blowing of whistle 150 and when signal H11 clears by the ringing of bell 129. When bell 129 stops ringing, the dispatcher knows that the train which is proceeding toward Y is in the track section C8 containing the switch. He can also follow the progress of the train by observing his train indicator. After the train has proceeded into the siding past the fouling point, switch SW automatically returns to its closed position, in the same manner as heretofore explained of which fact the dispatcher is advised by the blowing of whistle 150. The dispatcher now operates selector SL8 stepping commutators 100—108 back to position 1, signals H9 and H10 are released and take siding signal 115 is withdrawn. The train which has kept to the main line will now be at liberty to proceed, providing the block is clear in which case signal H10 will indicate proceed.
- Assume that the automatic train control system referred to in this invention is of some of the well known types, as the intermittent induction system of the Regan Safety Devices Co. installed for test on the Erie Railroad or the auto-manual system of the General Railway Signal Co. installed on various railroads, 17, 18, 110 and 112 represent the roadside inductors for such a system. Considering 18, under clear conditions its circuit is closed through circuit controller 113 closed when signal H9 indicates clear. Should a train, for which the take siding signal 115 is displayed and the signal H8 set at stop by the dispatcher, neglect to open switch SW, it will be automatically stopped by the automatic train control system because with signal H9 at stop the circuit of inductor 18 will be open. However, if the train does open the switch SW, signal H11 clears for the train to enter the siding and circuit controller 111 is operated closing the circuit for inductor 18 so that the train enters the siding without being stopped.
- In the case of the Regan system, which is a two or three position system, a track inductor, as 18, when in a closed circuit also acts as a resetting inductor. That is, if the train is running under a restriction, as low speed due to a previous stop inductor, upon coming into correspondence with a track inductor with a closed local circuit, the restriction is automatically relieved. Therefore, if a train operating under a train control restriction under the conditions described approaches inductor 18 with the signal 75

will be clear for the route into the siding, it will have its restriction cancelled as soon as it passes over inductor 19, and will enter the passing siding with its automatic train control in normal condition.

Assume that as a part of the train operating system, especially desirable at station locations, as station Y, the arrangement indicated in Fig. 6 is used, transformer TF being substituted for transformer TF₄, contacts 202 and 205 and connected conductors of circuit controlling relay RC being substituted for contacts 96 and 97 and connected conductors of selector controlled instrument SL₆, and relay RC being controlled by track relay T₈ and track relay T₉ (not shown) for section C₉. As the trains pass through the station Y on the main line or to and from the siding in sections C₈ and C₉ the relays for these sections are operated de-energizing relay RC so that its contacts 202 and 205 are closed between conductors 201 and 203 and conductors 206 and 204 respectively, connecting transformer secondary S to the dispatcher's communicating circuit, conductors D₁ and D₂. As transformer TF (now substituted for transformer TF₄) is a part of the intermediate circuit for section C₈, C₉, etc., trains within these sections are in a position to initiate communication with the dispatcher and report their location. For example, the train may report it is entering the passing siding, has entered the passing siding, is leaving the passing siding, etc. The intermediate circuit for sections C₈, C₉, etc., is but partly shown comprising track rails, conductors 88 and 89, condensers K, conductor 90, contact 91, conductor 92, transformer primary P (of TF, Fig. 6), conductors 93 and D₃, etc. This circuit completed requires a connection from conductor D₃ to the track rails, identical in arrangement with that shown, viz., conductor 93, transformer primary P, conductors 92, etc., but located at the right of the diagram Fig. 5. The insulated joints in the track rails are bypassed (not shown) by condenser C as illustrated in Fig. 1 or by resistance r as indicated in Fig. 3.

As they relate to the dispatcher's selective system, Figs. 1 and 5 are only schematic in the showing of instruments SL₁, SL₂, etc. Several systems of dispatcher's selective apparatus are in service on the railroads for telephone purposes. In these systems selectors are located at various stations with which it may be desired to hold conversation. Each selector is responsive to a certain coded call only. When the dispatcher desires to talk with a certain station he causes a certain code of electric impulses, corresponding to the code of the selector in the station being called, to be sent out over the main circuit. The selector responds by closing an electric contact to ring a bell to call the attendant. In my invention I make use of the contact on a selector of this general type to close an electric circuit for a stepping up relay or instrument like SD already explained which itself controls electric circuits. On the first operation of the selector its contact energizes the stepping up relay to an abnormal condition to close and open circuit contacts. In the case of a stepping up relay of two positions, on its second operation the selector restores the stepping up relay to its normal condition, causing those circuits which were closed in the abnormal condition to be opened and those which were open in the abnormal condition to be closed.

On return of the commutator segments to position "one", the normal position, commutator

108 opens the circuit of transmitter 110 producing a well defined click which may be heard by the dispatcher. Further, as indicating when position "one" is reached, the gong connected with the operating electro-magnet, either 169 or 155, will not sound for position "one" for the reason that the transmitter 110 is cut out before the armature falls, causing the hammer to strike the gong. In the case of the use of controlling instruments of more than one step, as in Fig. 4, the selector key CB is arranged with an operating lever such that in practice the position of this lever corresponds with the position of the commutators of the instrument SD. In this way a check is provided in the dispatcher's office on the position of the commutators of SD.

Instead of using a third conductor D₃, the annunciator conductor 14 may be connected directly to the dispatcher's main wire D₂ when the selector SL₁ is operated. Also, instead of using dispatcher's wire D₁ for the annunciator the common wire for the signal system may be used, and probably would be used in practice.

Although the circuits are illustrated in connection with a single track, it will of course be understood that the invention is applicable to two or more tracks.

What I claim is:

1. In a communicating system for railways, the combination of a stretch of track for a train, a dispatcher's selective system adapted to be connected with each one of a series of intermediate circuits, including the track rails, and communication receiving apparatus on the train inductively associated with said track rails responsive to communicating energy impulses originating in the dispatcher's selective system.

2. In a system adapted for communication between a railway train and the dispatcher, the combination comprising a dispatcher's communicating system, a communication receiving and transmitting circuit on the train, an intermediate circuit in inductive relation with said train circuit, and selective devices connecting the dispatcher's communicating system with the intermediate circuit.

3. In a system adapted for communication between the dispatcher and a railway train, the combination comprising a dispatcher's communicating circuit including selective apparatus for any one of a series of track districts, an intermediate circuit including the track rails for each of said districts adapted to be selective connected with the dispatcher's communicating circuit, and a communication receiving and transmitting circuit on the train in communicative relationship with said track rails, whereby communication may be had between the dispatcher and a train on a selected portion of the railway track.

4. In a train communicating system a stretch of track for a train, track section circuits in said stretch, conductors parallel thereto, a circuit connection from the rails of each track section to one of said conductors, a primary coil in each circuit connection, a secondary coil therefor, in inductive relation with each primary coil, a normally open circuit from each secondary coil to said conductors, movable contacts and a relay connected with each track section circuit controlling each secondary coil circuit, a transmitting and receiving set on the train having a circuit inductively connected with said track rails and a transmitting and receiving set connected to said conductors whereby communication may be carried

on between the train and an outside station, while the train is running over any of said track sections.

5. In a system adapted for transmitting energy impulses between the two ends of a railway train, the combination comprising an inductor in circuit with transmitting apparatus on one end of the train, a second inductor in circuit with receiving apparatus on the other end of the train, and an intermediate circuit, including the track rails multiple with which said two inductors are in direct inductive relation, for conveying said impulses between the two ends of the train.

6. For a train communicating system the combination comprising an intermediate circuit, of which the track rails in multiple form a part, a transmitting set on one end of the train, a receiving set on the other end of the train, and means inductively connecting said sets with said intermediate circuit through an air-gap over said track rails.

7. In a system adapted for communication between a railway train and a wayside station, the combination comprising an intermediate circuit, transmitting apparatus on the train in circuit with an inductor inductively influencing said intermediate circuit, receiving apparatus in the wayside station, and selectively operated means associated with said intermediate circuit and controlled from the wayside station for connecting said intermediate circuit with said station apparatus.

8. In a system adapted for communication between the front end and rear end of a train, the combination comprising a transmitting and receiving set on each end of the train and an intermediate circuit in inductive relation with said transmitting and receiving sets, said intermediate circuit consisting of a section of track rails and a conductor, the latter connecting to the track rails at the ends of said section.

9. In a means for carrying on communication between a railway train and a wayside station, a track system comprising a series of related intermediate circuits, each including a section of track rails inductively associated with train devices and connected at each end to a conductor, a circuit for the wayside station, and a transformer one coil of which is in the intermediate circuit and the other adapted for connection in the circuit for the wayside station.

10. In a system adapted for communication between the two ends of a railway train and between the railway train and a wayside station, the combination comprising transmitting and receiving circuits on each end of the train, a series of intermediate circuits on the wayside each in inductive relation with said train circuits as the train progresses over the railroad, transmitting and receiving circuits for the wayside station, and devices selectively controlled from the wayside for connecting said intermediate circuits with said wayside station circuits.

11. In a system adapted for communication between the two ends of a railway train and between the railway train and a wayside station, the combination comprising transmitting and receiving circuits on each end of the train, a series of intermediate circuits on the wayside each in inductive relation with said train circuits as the train progresses over the railroad, transmitting and receiving circuits for the wayside station, and devices controlled some by the train and some from the wayside for connecting said intermediate circuits with said wayside station circuits.

12. In a means for carrying on communication between the front end and rear end of a railway train, a track system comprising a series of track districts, a track circuit section in each district, a conductor connected to the rails at each end of each district to form a complete circuit including the track rails of said district and said conductor, a relay controlled by said track circuit section, and a circuit controlling contact operated by said relay so arranged in the connection between said conductor and the track rails that while a train occupies the track circuit section said connection is broken and the circuits for the two adjacent track districts are thrown together forming one complete circuit.

13. In a system for carrying on communication between the two ends of a railway train or a railway train and a wayside station, an intermediate circuit in the track system comprising the rails in a block signaled stretch of track, a conductor insulated from said track rails extending along the stretch of track, cross conductors connecting said conductor with the track rails, and means preventing the flow of block signaling current from the track rails into said conductor.

14. In a system adapted for communication between a railway train and a wayside communicating station in combination, a train set comprising a transmitter, a receiver, a source of electrical energy, an inductor and a circuit connecting said inductor and source of energy to said transmitter and receiver; an intermediate circuit inductively associated with said inductor and comprising, a section of track rails, a conductor connecting to the rails at both ends of said track sections, and a transformer coil in series in said circuit; a wayside circuit connected with said wayside communicating station; and means for connecting said wayside communicating circuit to another coil of said transformer.

15. In a system for carrying on communication between the two ends of a railway train, an intermediate circuit in the track system comprising the two rails in a section of track, a wayside conductor insulated from said track rails extending along the section of track, and a cross conductor connecting each track rail through a condenser with said wayside conductor at each end of said section.

16. In a system for carrying on communication between the two ends of a railway train enroute over a stretch of track, a wayside system comprising a series of intermediate circuits consisting of, the two track rails, a wayside conductor insulated from said rails extending along said track, and a cross conductor connecting between said track rails and said wayside conductor at intervals throughout said stretch.

17. In a system for carrying on communication between the two ends of a railway train, a stretch of track for said train, and a wayside system comprising a series of intermediate circuits consisting of, the two track rails, a wayside conductor insulated from said rails extending along said stretch, a cross conductor connecting between said track rails and said wayside conductor at intervals throughout the stretch, and track section circuits in said stretch controlling said cross conductor connections.

18. In a means for carrying on communication between a railway train and a wayside station, an intermediate circuit in the track system comprising the two rails in a section of track, a wayside conductor insulated from said track rails extending along said section of track, a cross

conductor connecting said track rail through a condenser with said wayside conductor at each end of said section, and a transformer, one coil of said transformer being in the intermediate circuit and the other coil adaptable for connection to said wayside station.

19. In a system for communicating between a wayside station and a railway train, a stretch of track, a series of intermediate circuits for said stretch, a selective system for the wayside station, including a prescribed selector for each intermediate circuit selectively controlled adapted to connect such corresponding intermediate circuit to said wayside station, and a train circuit in inductive relation with each of such intermediate circuits of said series as the train progresses through the stretch.

20. In a system for communicating between a wayside station and a railway train and/or between the two ends of a railway train, the combination comprising an intermediate circuit including the two rails of a section of track and a conductor connected to said rails at each end of said section, communication apparatus at the wayside station, means adapted to connect the wayside station apparatus with the intermediate circuit, and communicating apparatus on each end of said train, said last mentioned communicating apparatus being in circuit with an inductor in inductive relation with each track rail.

21. In a system for communicating between the two ends of a railway train on a stretch of track and/or between the railway train and a wayside station, an intermediate circuit comprising conductors along said stretch, a transformer in circuit with said conductors, and means at the end of said stretch connecting the conductors together, said means being adapted to join said circuit to an adjacent similar intermediate circuit, changing said two intermediate circuits into one intermediate circuit, and to eliminate the transformer from said first named circuit while the two intermediate circuits are joined.

22. In a system for communication between the two ends of a railroad train and said train and a wayside station, the combination comprising, a stretch of track for a train divided into districts, an intermediate circuit for each district, communication transmitting and receiving means on each train end in communicative relation with the intermediate circuit for one or more of said districts as the train travels through the stretch, a wayside station including a communication transmitting and receiving means adapted to be connected to said intermediate circuits, and means controlled from the station for connecting said station transmitting and receiving means with the intermediate circuits for some of said districts and means automatically controlled by the train for connecting said station transmitting and receiving means with the intermediate circuits of other of said districts.

23. In a train operating and dispatching system for railways, the combination comprising, a stretch of track for a train, track section circuits in said stretch, a first wayside circuit controlled by said track section circuits for locating said train, an intermediate circuit also controlled by track section circuits of said stretch for communicating with said train, communicating devices on said train electrically related to said intermediate circuit as the train travels over the railroad, a second wayside circuit connecting to a train locating device, a dispatcher's communicating and selective system, and selectors op-

erative in said selective system, one of said selectors being adapted to connect said first wayside circuit with said second wayside circuit to determine the location of the train, and another of said selectors being adapted to connect said dispatcher's communication system with the intermediate circuit that the dispatcher may communicate with said train after said train is located.

24. In a train operating and dispatching system, the combination comprising, a dispatcher's communicating circuit including selective apparatus for any one of a series of track districts, an intermediate circuit for each track district, adapted to be selectively connected to the dispatcher's communicating circuit, and a communication receiving and transmitting circuit on the train adapted to be in inductive relation with each intermediate circuit, whereby communication may be had between the dispatcher and a train on a selected portion of the track, and circuit means, the characteristics of which vary with the location of the train in the district occupied by the train, selectively connectable to an indicating instrument enabling the dispatcher to determine the district in which the train is located before the intermediate circuit for said district is connected to the dispatcher's communicating circuit.

25. In a system for communication between a wayside station and vehicles in a stretch of track, means for each vehicle adapted to transmit communications to and receive communications from the wayside station, a wayside station means for transmitting communications to and receiving communications from said vehicles, and means controlled from the wayside station for placing the transmitting and receiving means of said station in relation for communication with any one of said vehicles, or simultaneously with any several or all of said vehicles.

26. In a system for communication between a wayside station and railway trains in a stretch of track, a series of sections in said stretch each with an intermediate circuit, communication means on each train adapted to be in communicative relation with said intermediate circuits, a communication zone for each train traveling with the train and comprising at some times one and at other times more than one of said intermediate circuits, communication means in the wayside station, and means controlled from the wayside station for placing said wayside station communication means in communicative relation with the intermediate circuit for any one, several, or all of said trains.

27. In a railway dispatching system, a stretch of track for a train, including a main track and a side track connected together by a switch, and means permitting the train dispatcher in a wayside station to communicate with the engineman on the locomotive of said train and instruct him to operate said switch and take the train in on the siding, said means comprising a transmitting and receiving communicating means carried on the locomotive, a transmitting and receiving communicating means in the wayside station, and a communication zone for the train, traveling with the train, in which said wayside communicating means is adapted to be placed in communicative relation with said locomotive carried means by devices located within said zone but controlled from said wayside station.

28. In a means for communication between a wayside station and any one, or any several, of

- a plurality of trains in a stretch of track, comprising, a circuit for the wayside station, an intermediate circuit for each of said trains, a transformer in each intermediate circuit, a relay 5 adapted to connect each transformer with said circuit for the wayside station, and a selector operatively associated with each relay, each selector being responsive to a different prescribed electric current to control the associated relay.
- 10 29. In a system for communication between the rear end and the head end of a railway train or between either or both ends of the railway train and a wayside station, a stretch of track for the train divided into districts, an intermediate circuit for each district, a transformer associated with each intermediate circuit, means operative by the train connecting adjacent intermediate circuits together during the interval that the train is passing from one adjacent district to 15 the other, a transmitting and receiving communication set on each train end in inductive relation with the intermediate circuit for the district the train is occupying, a transmitting and receiving communication set in the wayside station, and 20 means including said transformer and a selectively operated relay, connecting the intermediate circuit for the section the train is occupying with said station communicating set.
- 25 30. In a system for communication between a vehicle in a track stretch and a wayside station, transmitter and receiver means adapted to be in circuit with an inductor on the vehicle, transmitter and receiver means in the wayside station, a plurality of mediums for conveying communication signals, each adapted for communicative relationship with said inductor, and controlling means in the wayside station adapted to selectively communicatively connect said mediums with the wayside station transmitter and receiver 30 means.
- 35 31. In a system for communication between a wayside station and railway trains in a stretch of track, means on each train and in said wayside station for transmitting and receiving communication signals, a circuit for each train within which communication signals from and to said train are confined, and means associated with said circuits and controlled from said station for optionally placing the transmitting and receiving 40 means of said station in communicative relation with the transmitting and receiving means of any one, or more than one, of said trains, said arrangement making possible a communication from said station to several trains at one time.
- 45 32. In a system for communication between the head end and rear end of trains on a stretch of track and between said trains and a wayside station, means on each train end and in said wayside station for transmitting and receiving communication signals, a communication channel for each train within which the means for the two ends of the train are in communicative relation, and means associated with said channels and controlled from said station for optionally placing the transmitting and receiving means of said station in communicative relation with the transmitting and receiving means of any one, or more than one, of said trains, said arrangement being such that communication may be carried on independently between the ends of any one or any several of said trains at the same time that communication is being carried on between said station and any other one or more than one of any other of 50 said trains.
- 55 33. In a system for operating railway trains over a stretch of track under the supervision of a train dispatcher, means for selective operation and communication means in the office of said dispatcher, a wayside circuit adapted to be connected with said means for selective operation and said communication means in said office, train locating means for said stretch adapted to reflect the location of said trains, a communication circuit for said stretch adapted for communicative relationship with said trains, and means 55 responsive to said means for selective operation over said wayside circuit to connect said train locating means with said office and said communication circuit with said wayside circuit.
- 60 34. A transmission system comprising in combination, the running rails of a stretch of track, remote sending and receiving stations each including a transmitting device, a receiving device and a circuit adapted to be connected to either of said devices and in direct inductive relation with each of said rails to induce alternating current therein in multiple when the transmitting device of that station is connected in the circuit of that station and to be responsive to current flowing through said rails when the receiving device of that station is connected in the circuit of that station whereby transmission from either station to the other may be effected through a circuit including said rails as parallel branches 65
- 65 35. An end to end transmission system comprising in combination the running rails of a stretch of railroad track, a train on said rails, a transmitting and receiving station at each end of said train, each station including a transmitting device, a receiving device and a circuit adapted to be connected to either of said devices at that station and in direct inductive relation with each of said rails to induce alternating current therein in multiple when the transmitting device of that station is connected in the circuit of that station and to be responsive to current flowing through said rails when the receiving device of that station is connected in the circuit of that station whereby transmission between the ends of the train may be effected 70 through a circuit including said rails as parallel branches.
- 70 36. In an inductive train telephone system, the combination with a stretch of track including the two running rails for a train, of a communication circuit associated with the stretch of track and electrically complete with the stretch of track either occupied by a train or unoccupied, said circuit comprising the two track rails in parallel and a common return path, operative with a train facing in either direction and running either forward or backward, and adapted to travel with a train moving over the stretch of track by additions to the circuit ahead of the train and subtractions from the circuit behind the train, inductors each comprising a winding on a magnetic core located in pairs at different points on a train in such manner that, with the train present on said running rails, the inductors are disposed adjacent to and separated by an air gap from the respective running rails and each, together with its respective rail, constitutes an electrical transformer wherein the winding serves as the primary winding and the rail as the secondary winding, telephone transmitting and receiving means connected in circuit with the pair of inductor windings at each train point, means including the transmitting means at one of said points and the associated inductors for inducing currents in said 75

communication circuit, and means including the receiving means at another of said points for inductively receiving said currents from the communication circuit whereby continuous telephonic communication may be carried on between the different points on the train while the same is moving along the stretch of track.

37. The combination, in a railway signal system, comprising a plurality of blocks, of a line conductor extending through each block, means in each block for connecting said line conductor in loop circuit relation with one of the rails of said block, a vehicle, signal means carried on the front and rear of said vehicle, the signal means both on the front and rear of the vehicle being arranged to co-operate with said rail whereby signaling may be effected between ends of said vehicle through the loop circuit comprising said line conductor and rail and means for joining the loop circuits of two adjacent blocks to form, a single loop.

38. Trackway apparatus for use in connection with an electrical system of signaling through the track rails between two points on a train, comprising, in combination with the usual insulated track sections each provided with the usual track circuit, two condensers connected in series across the rails of each track section, and a connection from the junction of each of said two condensers to a conductor including a front contact of the associated track relay.

39. Trackway apparatus for use in connection with an electrical system of signaling through the track rails between two points on a train, comprising, in combination with the usual insulated track sections each provided with the usual track circuit, two condensers connected in series across the rails of each track section, and means for connecting the junction of each said two condensers directly in front of and in the rear of a train with a conductor.

40. Trackway apparatus for use in connection with an electrical system of signaling through the track rails between two points on a train, comprising, in combination with the usual insulated track sections each provided with the usual track circuit, a condenser connected across each insulated joint, a pair of auxiliary condensers connected in series across the rails of each track section, and a connection from the junction of each pair of auxiliary condensers to a conductor including a front contact of the associated track relay.

41. Trackway apparatus for use in connection with an electrical system of signaling through the track rails between two points on a train, comprising, in combination with the usual insulated track sections each provided with the usual track circuit, a condenser connected across each insulated joint, a pair of auxiliary condensers connected in series across the rails of each track section, and means for connecting the junction of each pair of auxiliary condensers next in front of and next behind a train with a conductor.

42. In a system for communicating between a wayside station and either or both ends of a railway train or between the two ends of a railway train, the combination comprising, an intermediate circuit including the track rails in multiple, means adapted to connect said wayside station with said intermediate circuit, and means connecting said intermediate circuit with a train carried circuit comprising a train carried coil in direct inductive relation with each track rail.

43. The combination, in a railway signal system,

comprising a plurality of blocks, of an individual loop circuit extending through each block, and means whereby when a vehicle extends into adjacent blocks the loop circuits of said blocks are automatically connected together to form a single loop extending through said adjacent blocks.

44. The combination, in a railway signal system, comprising a plurality of blocks, of an individual loop circuit extending through each block, and means whereby when a vehicle extends into adjacent blocks the loop circuits of said blocks are automatically connected together to form a single loop extending through said adjacent blocks, said means being operable when the vehicle operates in a direction opposite to the direction of traffic out from one of said adjacent blocks to reestablish said individual loop circuits.

45. The combination, in a railway signal system, comprising a plurality of blocks, of an individual loop circuit extending through each block, and means whereby when a vehicle extends into adjacent blocks the loop circuits of said blocks are automatically connected together to form a single loop extending through said adjacent blocks, said means being operable when said adjacent blocks are individually occupied by separate vehicles to maintain an individual loop in each block.

46. The combination, in a railway signal system, comprising a plurality of blocks, a loop circuit in each block, of means for inductively supplying oscillations from a vehicle to the loop circuit of the block occupied thereby, and means controlled from a wayside station to relay said oscillations from the respective loop circuit to the loop circuit of another block.

47. The combination, in a railway communication system, comprising a plurality of blocks, of a loop circuit in each block, means carried by each vehicle to inductively supply oscillations to the loop circuit of the block occupied thereby and to receive oscillations from the loop circuit, and means selectively controllable to relay oscillations from the loop circuit of the respective block to the loop circuit of another block whereby oscillations transmitted from one vehicle may be transmitted to the loop circuit of said another block and received upon a different vehicle.

48. A trackway system of circuits for telephonically interconnecting stations on a moving train and a wayside station comprising, a series of normally closed wayside loop circuits each associated with a definite section of the track over which the train runs, train controlled devices associated with the track sections, means including said devices for temporarily altering said loop circuits so that a single loop circuit for a stretch of track of greater length than the train is always presented to the train as it moves along the track, and a circuit connecting said single loop circuit with the wayside station.

49. In a train telephone system, a stretch of track, a train moving along the track, a telephone set at one end of the train in direct inductive relation with both rails of the track, a telephone set on the other end of the train in direct inductive relation with both track rails, and a circuit for transmitting energy between said two stations comprising at all times the two track rails in multiple from a point substantially ahead of the train to a point substantially in the rear of the train and a conductive medium between said points.

50. A wayside system of circuits for simultaneously conveying non-interfering communication

- signals between two points on each of a plurality of railway trains in a sectionalized stretch of track comprising, an exclusive metallic circuit associated with each track section for conveying the signals between the two points on the train occupying the track section and to which such signals are confined, and circuit controlling devices for interconnecting a plurality of said circuits to temporarily disable their signal confining characteristics and permit the conveyance of signals between stations on a train or trains occupying a corresponding plurality of track sections.
51. In a train telephone system, a stretch of track divided into sections, an individual wayside circuit for each section inductively associated with telephone apparatus on trains occupying the respective sections, a wayside station, a line extending to said station, and switching devices associated with said circuits and remotely controlled from said station for connecting any desired number of said circuits to said line.
52. In a system of communication for railway trains, a stretch of track containing a plurality of sections, wayside circuits comprising the track rails and a conductor connected to said rails to form a loop circuit for each section, means in each circuit adapted to connect adjacent loops together as one loop, and communication means on each train adapted to be in inductive relation with each of said loops.
53. A trackway system of circuits for telephonically interconnecting stations at separated points on a moving train comprising, a series of normally closed wayside loop circuits each associated with a definite section of the track over which the train runs, train controlled devices associated with the track sections, and means including said devices for temporarily altering said loop circuits so that a single loop circuit extending beyond both train stations is always available to the train as it moves along the track.
54. In a system for carrying on communication between the two ends of a railway train, an intermediate circuit in the track system comprising the two rails in a section of track, a wayside conductor insulated from said track rails extending along the section of track, and a cross conductor connecting each track rail with said wayside conductor at each end of said section, said track rails being connected in parallel forming one side of said intermediate circuit and said conductor forming the other side of said intermediate circuit.
55. A transmission system comprising in combination, the running rails of a stretch of track, a sending circuit in direct inductive relation with each of said rails to induce alternating current in said rails in multiple and a receiving circuit remote from said sending circuit and responsive to current induced in said rails by said sending circuit.
56. In a system of communication for railways, a plurality of trains in a stretch of track, a wayside station, means for communication between the ends of each of said trains independent of said station, and means adapted to place said station in communication with any one or more of said plurality of trains independent of the communication carried on between the ends of other trains of said plurality.
57. In a train operating system in which a stretch of railway track is equipped with track switches and wayside signals operated by remote control from a central point over a dispatcher's line, a closed electrical circuit associated with the stretch of track and disposed so as to cooperate with telephone apparatus carried by trains operating through the stretch, means controlled over said line for connecting said circuit to the line, and means including said line and the circuit connected thereto for carrying on direct two way telephonic communication between moving trains in said stretch of track and said central point.
58. In a system for regulating the movement of trains over a stretch of railway track including a track switch connecting with a siding in which the position of the switch is controlled from a central point over a control circuit, a communication circuit associated with the stretch of track and disposed so as to inductively cooperate with telephone apparatus carried by trains moving through the stretch, means controlled from said central point over the control circuit for connecting said two circuits together, means controlled by a train in said stretch for connecting said two circuits together, and means including the connected circuits for carrying on direct two way telephonic communication between said central point and a train moving through the stretch of track.
59. In a train telephone system, a stretch of track for a train, a train on the track, a telephone transmitting device at one point on the train, a telephone receiving device at another point on the train, and a circuit for conducting current from said transmitting device to said receiving device comprising the two track rails and a common return path so related to said rails that current from the transmitting device flows through the track rails in multiple at points substantially ahead of and in the rear of the train.
60. In a train operating system, a stretch of railway line, a train in said stretch, a wayside station, apparatus for transmitting and receiving electric current at two different points on said train and in said wayside station, a circuit on said train at each of said points connected with the apparatus at that point, a circuit connected with the apparatus in the wayside station, a wayside circuit for said stretch of track comprising a plurality of conductors including the track rails of the stretch and a wayside conductor connected to said rails at each end of the stretch, said train carried circuits being operatively associated with one of said conductors for conveying the electric currents between the apparatus at said train points, and means for placing the circuit connected with the apparatus in the wayside station in electrical relation with said wayside circuit for conveying electric current between said wayside station apparatus and the apparatus at said train points.

ARCHIBALD G. SHAVER.

CERTIFICATE OF CORRECTION.

Patent No. 2,124,449.

July 19, 1938.

ARCHIBALD G. SHAVER.

It is hereby certified that error appears in the printed specification of the above numbered patent requiring correction as follows: Page 2, first column, line 43, for the words "and and the" read and the; and second column, line 3, for "and" read to: page 8, second column, line 14, for "signals H19" read signals H9; page 9, second column, line 53, claim 3, for "selective" read selectively; page 10, first column, line 11, claim 5, after "rails" insert the word in; and that the said Letters Patent should be read with this correction therein that the same may conform to the record of the case in the Patent Office.

Signed and sealed this 22nd day of November, A. D. 1938.

Henry Van Arsdale

(Seal)

Acting Commissioner of Patent.
